CONDENSER ASSEMBLY CONTROL.

Application filed April 6, 1927. Serial No. 181,390.

This invention relates generally to control mechanism for radio condenser assemblies, in which a plurality of variable condensers are used. It relates more particularly to panel 5 controls for such assemblies where two or more variable condensers are used, each condenser being of the type consisting of a set of fixed spaced plates and a set of rotatable spaced plates, the fixed plates being alternately 10 arranged in respect to the movable plates and each plate being insulated from adjacent plates by air or other dielectric.

It is the object of this invention to provide an improved and novel control mechanism 15 for such condenser assemblies, whereby all of the movable plates of the various condensers can be simultaneously moved or the movable set of plates of any one of the condensers can be independently moved.

20 To this end, the invention consists in the novel devices and novel combinations of devices defined in the claims and hereinafter described and illustrated in the accompanying drawings, wherein like reference characters refer to the same or similar parts throughout the various views and, in which,

Fig. 1 is a plan view of one embodiment of the present invention applied to one type of condenser assembly, certain of the parts 30 being broken away and shown in section;

Fig. 2 is a view in front elevation of the device;

Fig. 3 is a vertical section taken on line 3—3 of Fig. 1, as indicated by the arrows;

Fig. 4 is a plan view of one embodiment of the present invention applied to another type of condenser assembly, certain of the parts being broken away and shown in section, and,

Fig. 5 is a vertical section taken on line 5—5 of Fig. 4, as indicated by the arrows.

Referring to the drawings, Figures 1, 2 and 3, a pair of U-shaped supports 6 are illustrated, the said supports being aligned and having secured thereto at their upper ends and extending therebetween the two bars 7 composed preferably from insulating material. The supports 6 are bent outwardly and then downwardly from their upper ends. Secured between the bars 7, as by angle brackets 8, are three pairs of cross bars 9, each of the said bars 9 being also preferably formed of insulating material. Variable condensers A, B and C of any common type of construction are secured to each pair of bars 9. Each condenser A, B and C, as

illustrated, comprises a set of spaced fixed condenser plates 10 secured at spaced intervals, in turn, on bolts 11 secured to and extending between pairs of cooperating bars 9, the said plates being spaced from one another by spacing washers 12, and movable condenser plates 13 spaced from one another by washers 14 and secured to shafts 15 or 16 journaled respectively in each pair of bars 9. Shaft 15 of condenser A, the forward condenser, extends forwardly from the forward bar 9 for a purpose to be hereinafter described. The movable and fixed plates of each condenser A, B and C are alternately 70 arranged in respect to one another, each plate being insulated from its adjacent plates by an air dielectric. As a shaft 15 or 16 of any one of said condensers A, B or C is turned, the set of rotatable plates secured to 75 the shaft moved will be rotated so as to vary the capacity of the condenser. It will be understood that by connecting the condensers A, B, and C up with a radio receiving set, in the usual manner, and by properly adjusting the various movable sets of plates 10 of the three condensers A, B and C, that the movable plates may be adjusted to effect resonance with a received signal and with each other. It will, of course, be understood that 85 different types of variable condensers may be used in place of the condensers A, B and C described.

Secured to the forward outer end of shaft 16 of condenser B is an arm 17 having secured thereto at its outer end the forwardly projecting bar 18 composed preferably of insulating material. Secured to the forward end of shaft 16 of condenser C is an arm 19 preferably of slightly greater length than 90 arm 17 and having secured thereto at its outer end the forwardly projecting bar 19 also composed preferably from insulating material. The assembly consisting of the supports 6, bars 7 and 9 and the condensers 95 A, B and C will be so situated in a radio receiving set that the condensers will project immediately rearwardly from the front panel 20 of the set, the front panel having a comparatively large circular opening provided therein and the forward portion of shaft 15 extending centrally through said opening. Journaled at the forward end of shaft 15, a main control dial 21 is provided, the said dial being of such size as to just fit 100 over the circular opening in panel 20 and being so placed as to closely abut the panel. 105

The dial 21 has a central substantially cylindrical forwardly projecting portion therein, is beveled at its outer faced portion and is preferably provided with a conventional 5 half circumferential scale 21^a on said outer faced portion, the said scale being adapted to cooperate with an arrow or other designation 22 provided at the upper side of the panel 20 closely adjacent the outer circumference of the dial. Three shafts 23, 24 and 25 are journaled in the cylindrical portion of the main dial 21 and are preferably set at approximately 120 degree angles to each other. The said shafts project rearwardly 10 from the rear side of the dial 21 different lengths and each has fixed thereto at its rear end a cylindrical cam 26 secured off center to the shaft, whereby as the shaft is rotated, the cam will be eccentrically turned. The 15 rear end of each cam 26 is provided with a projecting flange and small coil pressure springs 27 are provided extending about the various shafts 23, 24 and 25 and reacting between the forward sides of the cams and 20 the rear side of the main dial 21. Knobs 28 are secured as by set screws to the forward ends of the shafts 23, 24 and 25, the said knobs closely abutting the forward side of the cylindrical portion of the main dial 21 25 and each knob 28 having a small pointer 28^a thereon, adapted to cooperate with an arcuate scale 29 formed on the face of the cylindrical portion of the main dial 21 adjacent each of the knobs 28.

An arm 30, journaled on the forward portion of shaft 15 rearwardly from the rear side of dial 21, is secured at its outer end to the bar 19. A second arm 31 is journaled on the shaft 15 immediately rearwardly from 40 the arm 30 and is secured at its outer end to the forward end of the bar 18. A third arm 32 is secured to the shaft 15 immediately rearwardly of arm 31 as by a set screw. The arms 30, 31 and 32 have elongated slots 45 30^a, 31^a and 32^a respectively, formed therein and extending radially to the axis of the shaft 15. The width of the slots 30^a, 31^a and 32^a are approximately equal to the diameter of the cams 26. One of said cams fits within 50 each of the slots 30^a, 31^a and 32^a and the flanges on the cams extend rearwardly from the arms 30, 31 and 32 to prevent forward removal of the cams from the respective slots. The two arms 30 and 31 are so bent 55 that when the arms are positioned in such a manner that the slots 31^a and 30^a extend at 120 degree angles to each other, as indicated in Fig. 3 of the drawings, the two bars 18 and 19 will extend parallel to each other, the 60 bar 18 being inwardly spaced from bar 19, and both bars being within the cutline of forward U-shaped support 6 and mounted for free swinging movement about a semi-circular arc. A spring brake 33 is secured 65 at one end of the forward end of a bar 7 and

is adapted to bear against the inner side of the main dial 21 to hold the dial under some little tension from rotation after the dial has been turned to a given position.

Operation.

Arms 17, 50 and 32 are adjusted on their respective shafts 16 and 15 so that when the main dial 21 is turned so that the number 100 on the scale 21 registers with the arrow 70 22, the upper edges of the various sets of movable condenser plates 13 will be substantially parallel with the upper edges of the stationary condenser plates 10, and the movable condenser plates will be projecting 75 downwardly between the various fixed condenser plates. In such position, knobs 28 will all be swung to the extreme counterclockwise position, as indicated in Fig. 2. When now it is desired to pick up a station 80 on the radio receiving set, the main control dial alone will be turned. The springs 27 will be of sufficient tension so that as the main dial 21 is turned, the various cams 26 will not be turned and, accordingly, the arms 85 30, 31 and 32 will be swung with the main dial, thereby swinging the bars 18 and 19 and arms 17 and 50 and causing all the shafts 16 and 15 of condensers A, B and C to turn to swing the various sets of movable condenser plates 13 simultaneously. Inasmuch 90 as nearly all radio stations may be picked up by a receiving set wherein several condensers are used, when the movable plates of the several condensers are all set at relatively 95 100 the same position in respect to their cooperating fixed plates, it will be very easy by merely turning the main control dial 21 to pick up practically every station which the receiving set is capable of receiving, so that the particular station picked up is capable 105 of being heard, at least, indistinctly. After a particular station has been picked up in this manner, it is desirable to secure a fine adjustment between the various condensers 110 115 so that the best possible reception will be obtained. The spring brake 33 will hold the main control dial 21 at the adjusted position. One of the knobs 28, as for example the knob 28 secured to shaft 23, may now be turned 120 in a clockwise direction to secure the best possible adjustment of the movable condenser plates of the condenser A. As the knob is turned, the shaft 23 will be rotated thereby causing the cam 28 secured to the shaft to be rotated causing the arm 32 to be swung in respect to the shaft 23, due to the eccentric action of the cam. As the arm 32 is swung, the shaft 15 will be rotated, thereby swinging the movable set of condenser plates 13 of the condenser A. A fine adjustment of the movable set of condenser plates of the condenser A can thus be secured. The knob secured to shaft 24 can next be turned 125 130 to secure a fine adjustment of the movable

plates of condenser B. As the shaft 24 is turned, the cam 28 secured thereto will swing the arm 31 thereby causing the bar 18 to swing the arm 17, rotate shaft 16 of condenser B and to turn the movable set of condenser plates 13 of condenser B. In a similar manner, as the knob 28 secured to shaft 23 is turned, arm 30, bar 19 and arm 50 will be swung to rotate shaft 16 and movable condenser plates 13 of condenser C. All the various sets of movable plates of the three condensers can thus be finely adjusted in respect to each other without movement of the main control dial 21. If then it is desired to keep the same relative adjustment between the various movable condenser plates when picking up another station, the main control dial 21 may be swung and the movable sets of condenser plates will remain in the same relative adjustment to each other. When it is desired to tabulate the settings of the dials 21 and 28 of a particular station, so that the same can again be readily turned to without needless experimental adjustment of any of the movable condenser plates, the recording of the scale of the main dial 21 is noted together with the recording of the scales 29 of each individual knob or dial 28. When it is desired to find the same station again, the main dial can be readily turned so that the scale registers with the arrow 22 at the recorded point, while the various pointers 28 on the knobs 28 can be turned to register with the recorded points on the various scales 29.

Various types of hook-ups can be made between the main control dial 21 and sets of condensers. One different type of hook-up is illustrated in Figs. 4 and 5. Referring to said figures, three condensers D, E and F are illustrated. These condensers are mounted side by side on two spaced bars 35, each of said condensers including the fixed spaced condenser plates 36 mounted on bolts 37 secured to bars 35, the fixed plates being spaced apart by washers 38, and the movable condenser plates 39 spaced from each other by washers 40 secured to a shaft 41 pivotally mounted in the bars 35. The shaft 41 preferably of the center condenser E is forwardly extended and the main dial 21 is pivoted onto the shaft 41 in the same manner as in the previously described assembly to the shaft 15. In place of the arms 17, 50, 30, 31 and 32 and bars 18 and 19, used in the assembly illustrated in Figs. 1, 2 and 3, a slightly different construction is used. Straight arms 42, 43 and 44 are substituted for the arms 30, 31 and 32 respectively, each of said arms having slots 42^a, 43^a and 44^a therein corresponding to the slots 30^a, 31^a and 32^a in arms 30, 31 and 32 respectively. Arm 42 is preferably secured to shaft 41 of condenser E by a set screw, while the other two arms 43 and 44 are journaled

on the said shaft, the arm 44 having a sleeve portion fitting over a sleeve portion of the arm 43. Small sprocket wheels 45 are secured to each of the shafts 41 of condensers D and F and are driven off sprockets 46 and 47 respectively, secured to the sleeves of respective arms 44 and 43, by endless chains 48. The arms 42, 43 and 44 extend radially outwardly from the axial center of the shaft 41 of condenser E and, accordingly, there will be no interference between the arms as they are swung by respective cams 26, inasmuch as the arms are set at 120 degree angles to each other.

When the hook-up, illustrated in Figs. 4 and 5, is operated, as the main dial 21 is turned, the various arms 42, 43 and 44 will be turned, arm 42 rotating shaft 41 of condenser E, arm 43 rotating sprocket wheel 47 and causing the shaft 41 of condenser F to be driven through a chain 48 and a sprocket 45, while arm 44 will cause sprocket 46 to be rotated thereby driving the shaft 41 of condenser D by the rotation of the sprocket 46, a chain 48 and a sprocket 45. In this manner, all the sets of movable condenser plates may be simultaneously turned and as the various individual shafts 23, 24 and 25 are turned, the various sets of movable condenser plates of the various condensers D, E and F may be independently adjusted, due to the eccentric action of cams 28.

Although but two types of assembly are illustrated, applicant's main dial with the knobs 28, shafts 23, 24 and 25, cams 26 and 27 may be used with practically any type of condenser assembly by merely providing different type of driving mechanism off the cams 26 to the sets of movable condenser plates.

The inventor does not wish to limit himself to the use of his device in connection with merely an assembly of three variable condensers, inasmuch as by slight modifications, the same can be used where any number of condensers, more than one, are used.

The device has been amply demonstrated in actual practice and has been found to be very efficient and successful for the purposes set forth. The device is of cheap and simple construction and can be readily made and assembled.

It will, of course, be understood that various changes may be made in the form, details, arrangement and proportions of the various parts without departing from the scope of the present invention.

What is claimed is:

1. The combination with a plurality of independently movable elements of a radio condenser assembly, of a single rotatable main control dial, a plurality of means respectively connected to respective movable elements of said radio condenser assembly, and a plurality of individual control means

mounted in said dial and connected to respective first mentioned means, whereby all of said movable elements may be rotated together as said dial is turned, each of said 5 individual control means being so constructed that as the same is individually operated it will operate the respective means connected thereto to rotate one movable element independently of the other movable 10 elements.

2. The combination with a plurality of sets of rotatable radio condenser plates, of a rotatably mounted single main control dial, individual control dials journaled in 15 said main dial, means respectively connecting each of said individual control dials to one of said sets of movable condenser plates, whereby as said main dial is turned all of said sets of movable condenser plates will be 20 simultaneously rotated, each of said means being so constructed that as the particular individual control dial connected thereto is turned, one set of said condenser plates will be individually rotated in respect to said 25 other sets of condenser plates.

3. The combination with a plurality of sets of movable radio condenser plates, of a rotatably mounted main control dial, a plurality of individual control dials journaled 30 in said main dial, a plurality of suitably pivoted arms, means connecting one of said arms to each of said individual control dials, whereby as said main dial is turned all of said arms will be simultaneously swung, said 35 means being so constructed that as one of said individual dials is moved the arm connected therewith will be individually swung in relation to the other arms, and means connecting each of said arms respectively to 40 one of said sets of movable condenser plates to move the set of condenser plates as the arm is swung.

4. The combination with a plurality of sets of rotatable radio condenser plates, of a rotatably mounted main control dial, a plurality of individual control dials journaled 45 in said main dial, a plurality of suitably pivoted arms, means for eccentrically connecting each of said individual control dials to one of said arms, whereby all of said arms will be simultaneously swung as said main dial is turned, and individual arms will be independently swung as individual dials are turned, and means for transmitting motion 50 imparted to respective arms to respective sets of movable condenser plates to rotate the same.

5. The combination with a plurality of sets of movable radio condenser plates, of a rotatably mounted main control dial, individual control dials journaled in said main 60 dial, cams connected to each of said individual control dials, suitably pivoted arms adapted to be swung by respective cams as 65 said respective individual control dials are

turned and means for transmitting motion imparted to respective arms to respective sets of condenser plates to rotate the same.

6. The combination with a plurality of sets of movable radio condenser plates, of a rotatably mounted single main control dial, a plurality of shafts journaled in said main dial, individual means for turning each of said shafts, an eccentric connected to one end of each of said shafts, suitably pivoted 75 arms, each arm being adapted to be individually swung by one of said eccentrics as a shaft is turned and all of said arms being adapted to be simultaneously swung as said main dial is turned, and means for transmitting the motion imparted to respective arms to respective sets of movable condenser plates.

7. The structure defined in claim 6, and resilient means surrounding said shafts and 85 interposed between said main dial and said eccentrics.

8. The combination with a plurality of sets of rotatable radio condenser plates, of a suitably mounted shaft, a main control 90 dial mounted on said shaft, a plurality of individual control dial shafts journaled in said main dial, arms mounted on said first mentioned shaft for swinging movement, each of said arms having a slot formed 95 therein radially arranged in respect to the axis of said first mentioned shaft, each second mentioned shaft extending through a slot in one of said arms and cams secured to said second mentioned shafts, working 100 within said slots and adapted to swing respective arms as respective second mentioned shafts are turned, and means for connecting each arm to swing one set of movable condenser plates as the arm is swung.

9. The combination with a plurality of sets of rotatable radio condenser plates, of a rotatably mounted main control dial, a plurality of individual control dials journaled 105 in said main dial, a plurality of suitably pivoted arms, means for eccentrically connecting each of said individual control dials to one of said arms, whereby all of said arms will be simultaneously swung as said main dial is turned, and individual arms will be independently swung as individual dials are turned, shafts upon which each set of individual movable condenser plates are mounted, arms connected to each of said shafts and bars respectively connecting one 115 of said first mentioned arms with one of said last mentioned arms.

10. A radio condenser assembly and control, comprising three sets of fixed condenser plates, three sets of movable condenser plates 120 respectively pivotally mounted for cooperation respectively with said respective sets of fixed condenser plates, a centrally pivoted main dial, three individual control dial shafts journaled in said main dial, dials se- 125 130

cured to the outer ends of said shafts, cylindrical cams eccentrically mounted adjacent the rear ends of said shafts, three arms pivoted for swinging movement coaxially with said main dial, each of said arms having a radial slot therein within which one of said cams is adapted to work to swing the arm as the shaft to which the cam is secured is turned and means for rotating one of said three sets of movable condenser plates as each arm is swung. 10

In testimony whereof I affix my signature.

HARRY H. BUSSE.
